(57) **CLAIM**

The ornamental design for a weighted plate, as shown and described.

DESCRIPTION

FIG. 1 is a front perspective view of a weighted plate in accordance with the first embodiment;

FIG. 2 is a top plan view of the weighted plate of FIG. 1;
FIG. 3 is a bottom plan view of the weighted plate of FIG. 1;

FIG. 4 is a front view of the weighted plate of FIG. 1;
FIG. 5 is a rear view of the weighted plate of FIG. 1;
FIG. 6 is a left side view of the weighted plate of FIG. 1;
FIG. 7 is a right side view of the weighted plate of FIG. 1;
FIG. 8 is a front perspective view of a weighted plate in accordance with the second embodiment;

FIG. 9 is a top plan view of the weighted plate of FIG. 8;

FIG. 10 is a bottom plan view of the weighted plate of FIG. 8;

FIG. 11 is a front view of the weighted plate of FIG. 8;
FIG. 12 is a rear view of the weighted plate of FIG. 8;
FIG. 13 is a left side view of the weighted plate of FIG. 8;
FIG. 14 is a right side view of the weighted plate of FIG. 8;
FIG. 15 is a front perspective view of the weighted plate of FIG. 1 and the weighted plate of FIG. 8 in an assembled state;

FIG. 16 is a top plan view of the weighted plate of FIG. 15;
FIG. 17 is a bottom plan view of the weighted plate of FIG. 15;

FIG. 18 is a front view of the weighted plate of FIG. 15;
FIG. 19 is a rear view of the weighted plate of FIG. 15;
FIG. 20 is a left side view of the weighted plate of FIG. 15;
FIG. 21 is a right side view of the weighted plate of FIG. 15;
and,

FIG. 22 is an exploded perspective view of the weighted plate of FIG. 15 in an unassembled state.

The solid hatching of the figures are included to illustrate the surface of the claimed design. The solid hatching has no bearing on texture, finish, etc. The broken line portions of

(Continued)

the figures are included to show unclaimed subject matter only and form no part of the claimed design.
